UNITED STATES PATENT OFFICE.

ISAAC M. BOND, OF NORTH TAZEWELL, VIRGINIA.

FIRE-CRACKER.

No. 901,317.

Specification of Letters Patent.

Patented Oct. 20, 1908.

Application filed September 30, 1907. Serial No. 395,176.

To all whom it may concern:

Be it known that I, ISAAC M. BOND, a citizen of the United States, residing at North Tazewell, in the county of Tazewell and State of Virginia, have invented certain new and useful Improvements in Fire-Crackers; and I do declare the following to be a full, clear, and exact description of the invention, such as will enable others skilled in the art to which it appertains to make and use the same.

My invention relates to fireworks and more particularly to that class known as fire crackers.

15 The object of my invention is to provide an article of this class which may be more readily ignited, in which the loss due to unexploded crackers is avoided, and one which will produce a louder report upon detonation. This object is accomplished by the construction shown in the accompanying drawing wherein is shown a side view of a cracker made in accordance with my invention, the size being exaggerated, and a portion being shown in section.

By reference to the drawing it will be seen that the cracker 1, while retaining its round form in cross section is given a taper 2 toward either end. By this change in form, I provide a cracker wherein the lines of force at the moment of explosion have a tendency to accumulate within the points, finding the line of least resistance in a direction at an angle to the axis of the cracker rather than parallel therewith. This construction and condition permits me to give greater thickness to the walls 3 at the point of greatest diameter, and to compensate therefor by gradually decreasing the amount of wall material toward the ends. A similar taper is given the canal 4 within which is stored the explosive 5. Said canal taking the form of an elongated pocket having its greatest diameter midway the ends of the cracker and contracted at the ends to a diameter identical with that of the fuse 6.

My invention contemplates the use of a fuse 6 of the same length as the cracker body 1 and of the character now in use and well known.

The cracker body being completed, as described, the ends or tips 7 are dipped in a friction ignitable composition, such as used in the manufacture of matches, and a small section of the surface of the cracker given a 55 coating of abrasive material, and the article is ready for use.

In addition to the advantages heretofore pointed out, it will appear that the form given the cracker body is such as will prevent its premature ignition by contact with its fellows in storage or shipping, and which will insure it against damage by contact with damp surfaces. Again, it will be obvious that weather conditions will have little or no 65 influence upon a cracker constructed as described, since it is always possible to ignite one by frictional contact with a fellow even in violent storms.

Having thus described my invention, what 70 I claim as new and desire to secure by Letters-Patent, is:

1. A firecracker comprising a body having a powder-chamber, a fuse extending therethrough and exposed at both ends, and an 75 ignitable composition carried on each end of the body in touch with the fuse.

2. A firecracker comprising a body, exposed abrasive material on said body, a fuse running through said body and exposed at 80 both ends, and ignitable material carried by the body in engagement with the fuse.

3. In a fire-cracker, an explosive containing cell having an elongated form and decreasing in diameter from its center towards 85 its end, the inclosing wall of said cell varying in thickness from the middle portion of the cracker toward its ends, for the purpose set forth.

4. A hollow firecracker body, tapering 90 from its center toward its ends, the material of said body decreasing in thickness in the direction of taper, and a firing fuse.

In testimony whereof I have hereunto set my hand in presence of two subscribing 95 witnesses.

ISAAC M. BOND.
